James H. Patrie, Erie, Pa., assignor to
American Sterilizer Company, Erie, Pa.

Filed Sept. 12, 1973, Ser. No. 396,422

Term of patent 14 years

Int. Cl. D12—02; D15—07
U.S. Cl. D67—3 R

FIG. 1.

FIG. 2.

FIG. 3.

FIG. 1 is a perspective view of a combined dietary module and refrigeration unit and supporting frames therefor showing my new design;

FIG. 2 is a front elevational view thereof;

FIG. 3 is a side elevational view taken from the right of FIG. 2.

The handle and wheels are shown in broken lines in all views for illustrative purposes only and do not form a part of the claimed design.

The rear and undisclosed side of the dietary module is flat, and the undisclosed side of the refrigeration unit is identical.

I claim:

The ornamental design for a combined dietary module and refrigeration unit and supporting frames therefor, as shown and described.
